UNITED STATES PATENT OFFICE

95,903

DESIGN FOR A WHISKY GLASS

Frank L. Fenton, Williamstown, W. Va.

Application August 24, 1934, Serial No. 53,035

Term of patent 3½ years

To all whom it may concern:

Be it known that I, Frank L. Fenton, citizen of the United States and resident of Williamstown, in the county of Wood and State of West Virginia, have invented a new, original, and ornamental Design for a Whisky Glass, of which the following is a specification, reference being had to the accompanying drawing, forming part thereof, in which, Figure 1 is a perspective view of the whisky glass showing my new design. Figure 2 is a composite side view and longitudinal section of the same.

I claim:

The ornamental design for a whisky glass, as shown.

FRANK L. FENTON.
